CLAIM

The ornamental design for medical instrument, as shown and described.

DESCRIPTION

In a preferred embodiment, the nature of this product is as a medical instrument primarily useful for monitoring or treating medical patients.

FIG. 1 is a perspective view of a medical instrument embodying the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left right side elevational view thereof; and,

FIG. 7 is a right side elevational view thereof.

1 Claim, 4 Drawing Sheets
